UNITED STATES PATENT OFFICE.

LOUIS KOVACS, OF CHICAGO, ILLINOIS.

SLIDING SWITCH.

1,375,300.

Specification of Letters Patent. Patented Apr. 19, 1921.

Original application filed January 21, 1918, Serial No. 212,930. Divided and this application filed June 21, 1919. Serial No. 305,845.

To all whom it may concern:

Be it known that I, Louis Kovacs, citizen of Austria-Hungary, residing at Chicago, in the county of Cook and State of Illinois, 5 have invented certain new and useful Improvements in Sliding Switches; and I do hereby declare the following to be a full, clear, and exact description of the invention, such as will enable others skilled in 10 the art to which it appertains to make and use the same.

My invention relates to electric switches and in one of its general aspects aims to provide a simple and effective type of 15 switch having a slidable contact-closing member. In another aspect, my invention relates to secret switches and aims to provide an easily manufactured switch which will be operable by a sliding contact while 20 continuously concealing its mechanism from view, but without involving any uncertainty as to the operative position of the sliding contact. In this last named aspect, my invention also aims to provide a switch of such design 25 and compactness that it can readily be mounted in the cover of a so-called combination switch without increasing the size of the latter, thereby affording an additional series of steps which will correspondingly in- 30 crease the number of possible combinations obtainable by means of the combination switch.

Still other and to some extent more detailed objects will appear from the following specification and from the accompanying drawings, these drawings being reproduced from my copending application #212,930, which has matured into Patent No. 1,310,354, issued July 15, 1919, of which 40 the present application constitutes a division. In the drawings,

Figure 1 is a front elevation of a combination switch embodying the sliding switch of my invention and showing the same as it 45 will appear when mounted on a dashboard of an automobile or the like.

Fig. 2 is a central and vertical section through Fig. 1, showing also diagrammatically the connections to a storage battery 50 and to a spark plug as included in the circuit controlled by the combination switch.

Fig. 3 is a section taken vertically through Fig. 2 along the line 3—3.

Fig. 4 is an enlarged fragmentary section 55 taken along the lines 4—4 of Fig. 3.

Fig. 5 is a fragmentary similar section showing a desirable method of providing the contacts for the sliding switch of my invention.

In the embodiment of the drawings, the switch of my invention consists primarily of a pair of contacts 1 and 2 disposed substantially flush with the opposite sides of a channel 3 made of insulating material and hence adapted to be electrically connected by a metal ring 4 which forms the exterior 60 of a slide adapted to be moved back and forth within the said channel. The entire switch as thus arranged is here shown as mounted within the cover 5 of a dial switch 65 or so-called combination secret switch having two separately movable contact arms 6 and 7 adapted to close parts of a single series circuit. In this case, the circuit is shown as extending from a battery 8 to a pair of 70 contacts 9 adapted to be bridged by the contact 7, thence to a spark plug and from the latter to another pair of contacts adapted to be bridged by the contact arm 6. The two contact arms are controlled respectively 75 by separate handles 12 and 13 and the position of the contact arms is indicated to the initiated by pointers 14 and 15 moving respectively over dials 16 and 17 as described more in detail in my said copending application. The number of possible combinations therefore obtainable would be the 80 product of the number of indications or sections on the two dials.

While this number may be quite large in 90 itself, the protection afforded by such a combination switch has not always proven adequate, for the reason that it does not take a sufficient length of time for anyone to set one of the indicators (such as the indicator 14) successively on each of its indications, and to spin the combination indicator entirely around the circle in each case. Consequently, even with an apparently 95 large number of possible combinations, it 100 may take an intruder only a relatively short length of time to work the combination, so that this will not prove an adequate safeguard.

To overcome this, I desirably provide an 105 auxiliary combination switch also connected in series with the other contacts and correspondingly multiplying the number of possible combinations. For example, if the auxiliary sliding switch of Figs. 1 and 2 has 110

a sliding contact controlled in position by a knob 18 and has ten definite indicating positions for this knob, the number of possible combinations obtainable by the switch mechanism as a whole would be ten times what they would be without the use of this auxiliary switch. Consequently, the old expedient used by automobile thieves of trying out the whole range of combinations would 10 require far too much time to be effective when the ordinary range of combination switch is greatly increased by the combination-multiplying effect of my sliding switch.

In building the switch of my invention for 15 the above described purpose, I desirably mount within the cover 5 of the combination switch a channel member 19 of insulating material having its opening directed toward the front of the cover, and equip the cover 20 with an arcuate slot 20 extending in alignment with the center line of the channel. Projecting through this slot and slidably in it is a shank 21 which connects the knob 18 with an insulating spool 22 carrying a contact ring 4. Then I mount upon the channel member 19 the contact members 1 and 2 which form the circuit terminals connected by the contact ring 4 when the latter is in a predetermined position, these contact 25 members 1 and 2 being desirably flush with the bore of the channel so that their location cannot be felt by the hand moving the sliding members. To judge of the position of the sliding member, I provide the cover with 30 a series of markings, only one of which will correspond to the position in which the contact element 4 bridges across the contacts 1 and 2. Then I conceal the position of the contacts from view through the slot 20 by 35 a sliding plate 23 which is interposed between the front of the cover and the spool 22, and which therefore moves longitudinally of the channel and of the slot 20 when the knob is moved.

40 Thus arranged, it will be obvious from the drawings that by moving the knob 18 from one to another of the adjacent indicating markings on the cover, I can set the contact ring 4 at any one of a series of positions, in only one of which positions it would cooperate with the contact arms 6 and 7 in closing the circuit from the battery 8 to the spark plug 10. It will also be evident that the ordinary cover of the dial combination 45 switch readily affords a mounting for such a sliding switch, and that the auxiliary sliding switch can readily be added to such a combination switch without increasing the size of the combination switch. Furthermore, 50 the connections to the sliding switch can be simply and cheaply made by using

wire terminal screws having shanks of reduced diameter forming the contacts 1 and 2, as clearly shown in the enlarged view of Fig. 5. However, while I have illustrated and described the switch of my invention as being built in a curved form so as to embody the same compactly within the cover of a dial combination switch, and as having the cover of this combination switch as its own 70 cover, I do not wish to be limited to these or other details of the construction and arrangement here disclosed, it being obvious that the same might be modified in many ways without departing from the spirit of 75 the appended claims.

I claim as my invention:

1. In an electric switch, a channel-sectioned member of insulating material, a pair of wire terminals mounted thereon and extending substantially flush with the bore of the channel at opposite sides thereof, a concealing plate continuously closing the mouth of the channel and longer than the latter and having a perforation, a cover over the concealing plate having a slot in alignment with the said perforation and the axis of the channel and having indicating markings thereon, a handle member extending through said slot and perforation into the channel, and a metal switching element carried by the handle member and bridging the said wire terminals when the handle member is opposite a predetermined one of the indicating markings on the cover. 95

2. In a secret switch, a channel sectioned member of insulating material, a cover for the same equipped with a slot extending longitudinally thereof, a contact member disposed within the channel of the said member and slidable therein, a handle secured to the contact member and extending through said slot, a pair of wire terminals extending into the channel of the said member and disposed for contacting simultaneously with the contact member when the latter is in a predetermined position, and a strip of opaque material longer than the said slot and fast with respect to the contact member and disposed for concealing the interior of the channel sectioned member from view through the said slot. 100

105

3. An electric switch as per claim 1, in which the wire terminals comprise a pair of parallel screws threaded into the channel-sectioned member and having unthreaded stem portions disposed respectively at opposite sides of the bore of the channel. 110

115

Signed at Chicago, Illinois, June 18th, 1919.

LOUIS KOVACS.
